MULTISTAGE CONTROL DEVICE FOR POWER DRIVEN VEHICLES INCLUDING A PLURALITY OF PRIME MOVERS

Hans Nyffenegger, Winterthur, Switzerland, assignor to Schweizerische Lokomotiv- und Maschinenfabrik, Winterthur, Switzerland

Application October 3, 1938, Serial No. 233,101
In Germany October 7, 1937

7 Claims. (Cl. 60—97)

This invention relates to multistage control devices for power driven vehicles including a plurality of prime movers.

The vehicle comprises driving axles each of which or groups of which are driven by one or more prime movers the pressure fluid admission of which can be controlled in steps.

The control may, for example, be effected, as disclosed in United States Patent No. 1,634,736 by means of a displaceable control shaft carrying stepped cams. In control devices of this kind the number of control stages is obviously limited due to the space requirement for shifting the cam shaft. This holds true to a particularly great extent for the control stages for driving backwards for which in these circumstances it is usual to provide, for example, only two control stages. In the operation, a steam control which can be varied in steps only is liable to have a disturbing effect for the reason that the tractive effort, for example, of a locomotive may prove to either be too great or too small for maintaining the desired speed of driving, when a certain control stage or the next lower stage, respectively, is used, so that in such case the driving must be continued with the greater steam admission and throttling of the steam by means of the throttle.

In vehicles having no preferred direction of driving and in which the number of control stages for driving backwards is increased at the expense of the number of stages for driving forwards this deficiency is particularly inconveniencing. But also during starting, the small number of available control stages is unsatisfactory. This deficiency could be moderated by increasing the number of control stages but, as explained above, this is impracticable on account of want of space.

The object of the invention is to improve the fineness of gradation of multistage control of the tractive effort without resorting to expedients such as throttling the pressure fluid supply to the prime movers, and varying the number of stepped cams. This is accomplished, according to the invention, by the provision that the control devices of individual prime movers or groups of such engines are rendered adjustable to different control stages of pressure fluid admission at the same time.

Since for each control stage of steam admission or cut-off any steam prime mover produces a uniform tractive effort, within a speed range of an adequate extent, in an arrangement, according to the invention, comprising a plurality of such engines a highly uniform and finely stepped con-

trol of the tractive effort can be obtained by summation of individual tractive efforts.

A form of the invention is illustrated in the accompanying drawings by way of example only, in which

Fig. 1 is a schematic view of the control devices of two steam engines included in a locomotive;

Fig. 2 is a view of control parts of Fig. 1 in an intermediate position;

Figs. 3 and 4 each represent a view of a different form of control parts;

Figs. 5 and 6 illustrate diagrammatically the tractive efforts produced without and with the aid of the invention, respectively;

Figs. 7 and 8 each indicate diagrammatically a different control device for steam locomotives including a plurality of steam engines;

Fig. 9 illustrates a modification of the control device shown in Fig. 1, and

Fig. 10 is a view of the assembled parts of a steam admission control device according to the invention.

As shown in Fig. 1, inlet valves 1 and 2 of steam cylinders, one of which is shown at C, in Fig. 10, of two steam engines operatively connected with the axles of the vehicle to be driven (not shown) are adjusted by control shafts 3 by means of guide rollers 4 for admitting steam to the cylinders C in the direction of the arrows A, B (Figs. 1, 10). Each control shaft carries cams O, I, II corresponding to three different steam cut-offs. The control shaft 3 is displaceably arranged in bearings 5 so as to be adapted to be axially shifted by an auxiliary pressure controlled piston 6, through the intermediary of a coupling 7, in order to provide cooperation of either one of the cams O, I, II with the valve guide roller 4, 4a as desired. Driving movement is transmitted to the control shaft 3, via a gear wheel 3a and cooperating gearing means, from the crank shaft of the steam engine, in a manner not shown.

The auxiliary piston 6 is controlled by a piston valve 8 in a manner known per se by supplying a pressure medium through pipes 9' or 9" respectively to either one of the end faces of the auxiliary piston 6. The piston valve in turn is influenced step by step by stepped slide members 14, 14a by means of a pusher 12 which is pivotally connected to a resetting lever 11, at 10, and provided with a guide roller 13 or 13a. The two stepped slide members 14, 14a for adjusting the valves 1, 2, respectively, of the cylinders of the two steam engines are firmly connected one with

the other and are operated from a setting lever 15.

In Fig. 1 the two rollers 13, 13a are shown to be set on corresponding control stages I of the slide members 14, 14a. Accordingly each of the cam shafts 3 of the associated auxiliary pistons 6 are adjusted into corresponding positions in which the corresponding cams I of the two cam shafts 3 cooperate with the valves 1, 2, respectively. Thus both engines operate with equal steam admissions.

On close inspection of Fig. 1, it will be seen that although the rollers 13, 13a controlling the two engines, respectively, are set to the same stage I of the associated slide members, one of the rollers 13 rests against the right section of stage I of the slide member 14, whereas the other roller 13a rests against the left section of stage I of the other slide member 14a at a distance a from a point corresponding to the point of the right section of the same stage of slide 14 at which roller 13 is positioned.

Therefore, the stepped slide member 14a is displaced relative to the associated pusher 13a for a distance

$$a = \frac{1}{2} \times 2a$$

Thus, when the slide members 14, 14a are jointly displaced to the left by the lever 15 for a distance a , the roller 13 of the rollers 13, 13a is set on stage II, whereas the other roller 13a remains on stage I, as before, by merely shifting to the other section of this stage, as shown in Fig. 2. If, thereupon, the control movement is continued for a further step a the other roller 13a is also raised onto the higher step II.

In the position of the parts of the control device shown in Fig. 1, both engines operate by means of the same steam cut-off; in the position shown in Fig. 2 the valve 1 is set for admitting a different, for example, a smaller amount of steam than valve 2. In the third, that is, the last-named position, in which both rollers 13, 13a are raised onto stage II, both valves are again set for admitting an equal, but in the present instance, smaller amount of steam. From this it follows that in the position shown in Fig. 2 an intermediate stage of tractive effort is provided, so that in an arrangement, according to the invention, a greater number of control stages for setting the tractive effort, that is, a finer gradation of the tractive effort can be obtained. These different gradations are illustrated in the diagrams represented in Figs. 5 and 6.

In Fig. 5 are illustrated the control stages of tractive effort of a locomotive with two steam engines both of the five-stage control devices of which are always set to the corresponding steam cut-offs. By plotting the tractive efforts on the ordinate and the positions of the stepped slide members on the abscissa, the stepped line shown in Fig. 5 is obtained according to which along each stretch $2a$ the tractive effort, for example Z_{II} of the locomotive is constant. On the other hand, by constructing the control device as shown in Figs. 1 and 2 a more finely graded stepped line, as shown in Fig. 6 is obtained, due to the fact that in a position as indicated in Fig. 2 a further tractive effort equal to the mean value of the tractive efforts Z_I, Z_{II} of the stages I, II, respectively, is obtained which amounts to

$$Z_{I,II} = \frac{Z_I + Z_{II}}{2}$$

Therefore, additional intermediate stages of trac-

tive effort are obtained between the main stages of tractive effort.

It will be readily seen that in this way, for example, in a locomotive or power rail vehicle including a relatively great number of steam engines a very fine gradation of tractive effort can be obtained. If, for example, six steam engines are present, as schematically indicated in Fig. 7, a double amount of control stages of tractive effort is obtained if, for example, the group of 10 steam engines designated by b , on the one hand, and that designated by c , on the other hand, have admitted thereto the same volume of steam at each time. By admitting different volumes of steam to the two groups an additional intermediate control stage of tractive effort is obtained. If each group is provided with five control stages, ten different control stages to which the tractive effort can be adjusted are obtained, according to the invention.

With another arrangement of groups of steam engines operating with the same volume of steam admission at a time, for example, an arrangement of three pairs of engines, as shown in Fig. 8, fifteen control stages to which the tractive effort can be adjusted are obtainable by admitting the same volume of steam at a time to the steam engines designated by the same characters b, c or d . In this case, one or more pairs of engines can be run with the same volume of steam admission and the remaining pairs with a different volume, so that two intermediate control stages of tractive effort can be obtained between consecutive main control stages as provided without the aid of the invention.

The number of control stages can be still further increased, for example by running the six steam engines individually with different volumes of steam admission instead of in groups. In this way, between each two main control stages of tractive effort a maximum of five intermediate stages is obtainable.

Alternatively, instead of controlling the slide members 14, 14a and the rollers 13, 13a by means of a linkage 15, 15a, as shown in Figs. 1 and 2, this can be effected by means including a slide member in the form of a screw nut 14' provided with a longitudinal slot 14'' (Fig. 3). This member is screwed to a spindle 17 on which it is secured against relative rotation by a stud 16' on a bracket 16' interengaging with the slot 14''. The spindle 17, which is mounted in bearings 16, is rotatable by means of any suitable means, for example, by a handwheel 22, located at the driver's cab, and intervening bevel wheel drives 18. The spindles 17 of the control devices of the various steam engines are coupled together, for example, by means of couplings 19. Obviously the slide members 14' must be so adjusted relative to the spindles that the staggered relation thereof as indicated in Figs. 1 and 2 is obtained.

Alternatively, the control of the rollers 13 may be effected through the intermediary of a stepped cam 21 which is rotatable about a shaft 20 from the driver's cab (Fig. 4). This constructional form affords, like all the others, to transform the continuous movement imparted to the control handwheel by the driver to a stepped operation of the cam shaft 3.

In an arrangement as shown in Figs. 1 and 2, the control device is adjusted at a time to admission volumes which differ from each other only correspondingly to the difference between the effects of two consecutive main control stages. It is, however, also feasible to adjust the control

device to admission volumes differing from each other by more than would correspond to the difference between the effects of two consecutive control stages.

- 5 The adjustment of the sections of the control device leading to the various engines or groups of engines is effected by means of a single setting lever or by means of a control handwheel such as 22. Instead of effecting the control of 10 each steam engine by means of a separate auxiliary pressure controlled piston a single piston of this kind may be used for adjusting the cam shafts of a whole group of engines, as shown in Fig. 9.
- 15 Various changes and modifications may be made in the practice of my invention without departing from the principle or spirit thereof, by adding customary practice and established knowledge of the art to the present disclosure 20 and the scope of the appended claims is not to be regarded as limited except as specified therein.

I claim:

1. In a multistage control device for power driven vehicles including a plurality of pressure fluid operated prime movers and driving axles driven thereby prime mover units including at least one prime mover, individual control means correlated to each of said units for adjusting the pressure fluid admission of each prime mover included in the respective unit in steps of consecutive main cut-off stages, and means for commonly adjusting said individual control means of all of said units for a non-intermissive tractive effort of the vehicle by shifting said individual control means across coordinated main cut-off stages for unidirectional movement of said units, in relatively staggered relation, for obtaining intermediate cut-off stages of the device between the main cut-off stages of said units.
  2. In a multistage control device for power driven vehicles including a plurality of pressure fluid operated prime movers and driving axles driven thereby, prime mover units including at least one prime mover, individual control means correlated to each of said units for adjusting the pressure fluid admission of each prime mover included in the respective unit in steps of consecutive main cut-off stages, and a single adjusting member common to said individual control means for adjusting said individual control means of all of said units for a non-intermissive traction effort of the vehicle by shifting said individual control means across coordinated main cut-off stages for unidirectional movement of said units, in relatively staggered relation, for obtaining intermediate cut-off stages of the device between the main cut-off stages of said units.
  3. In a multistage control device for power driven vehicles including a plurality of pressure fluid operated prime movers and driving axles driven thereby, prime mover units including at least one prime mover, control means correlated to each of said units for adjusting the pressure fluid admission of each prime mover included in the respective unit, pressure controlled piston means included in at least some of said control
- means for controlling the same, and means for adjusting said control means to different fluid cut-offs regarding different units.
4. In a multistage control device for power driven vehicles including a plurality of pressure fluid operated prime movers and driving axles driven thereby, prime mover units including at least one prime mover, control means correlated to each of said units for adjusting the pressure fluid admission of each prime mover included in the respective unit, pressure controlled piston means included in at least some of said control means for controlling the same, control slides associated with said piston means, stepped members for controlling said control slides, a single adjusting member common to said control means and operatively connected with each of said stepped members for imparting said members a continuous movement which is changed to a stepped movement by said members for accordingly controlling said slides for the latter to adjust said control means to different fluid cut-offs regarding different units.
5. In a multistage control device for power driven vehicles including a plurality of pressure fluid operated prime movers and driving axles driven thereby, at least two prime mover units each including a like number of prime movers, separate control means correlated to each of said units, stepped members having an equal number of steps included in each of said control means for adapting said means to adjust the pressure fluid admission to equal volumes at a time for all said prime movers in said units, and means for adjusting said control means to different fluid cut-offs regarding different units.
6. In a multistage control device for power driven vehicles including a plurality of pressure fluid operated prime movers and driving axles driven thereby, pairs of prime movers associated with an individual driving axle of the vehicle, one of said prime movers of each of said pairs included in a unit of prime movers and the other one of said prime movers of each of said pairs included in a second unit of prime movers, and control means correlated to each of said units for adjusting the pressure fluid admission to equal volumes at a time for all said prime movers in said units, and means for adjusting said control means to different fluid cut-offs regarding different units.
7. In a multistage control device for power driven vehicles including a plurality of pressure fluid operated prime movers and driving axles driven thereby, prime mover units including at least one prime mover, control means correlated to each of said units for adjusting the pressure fluid admission of each prime mover included in the respective unit, and means for adjusting said control means to different fluid cut-offs regarding different units, the admission volumes supplied by said fluid cut-offs differing from each other by no more than the difference between the effects of two consecutive main control stages of said control means.

HANS NYFFENEGGER.
